(57) **CLAIM**

The ornamental design for an integrated radar detector and dash camera, as shown and described.

DESCRIPTION

FIG. 1 illustrates a perspective view of an example embodiment of an integrated radar detector and dash camera according to the present disclosure;

FIG. 2 illustrates a top elevational view thereof;

FIG. 3 illustrates a bottom elevational view thereof;

FIG. 4 illustrates a left side elevational view thereof;

FIG. 5 illustrates a right side elevational view thereof;

FIG. 6 illustrates a front side elevational view thereof; and

FIG. 7 illustrates a rear side elevational view thereof.

FIG. 8 illustrates a perspective view of a second example embodiment of an integrated radar detector and dash camera according to the present disclosure;

FIG. 9 illustrates a top elevational view thereof;

FIG. 10 illustrates a bottom elevational view thereof;

FIG. 11 illustrates a left side elevational view thereof;

FIG. 12 illustrates a right side elevational view thereof;

FIG. 13 illustrates a front side elevational view thereof; and,

FIG. 14 illustrates a rear side elevational view thereof.

In the drawings, the broken lines depict environmental subject matter that forms no part of the claimed design.
